CLAIM

I claim the ornamental design for a divot repair tool with oval body, as shown and described.

DESCRIPTION

FIG. 1 is a left front perspective view of a divot repair tool with oval body showing my new design;

FIG. 2 is a front elevational view thereof;

FIG. 3 is a right side elevational view thereof, it being understood that the left side elevational view is identical thereto;

FIG. 4 is a rear elevational view thereof;

FIG. 5 is a top plan view thereof; and,

FIG. 6 is a bottom plan view thereof.
